UNITED STATES PATENT OFFICE.

CHARLES HEIN, OF CORONA, ASSIGNOR TO HALE & MULFORD, OF NEW YORK, N. Y.

DESIGN FOR A BRACELET.

SPECIFICATION forming part of Design No. 11,779, dated May 18, 1880.

Application filed November 11, 1879. Term of patent 14 years.

To all whom it may concern:

Be it known that I, CHARLES HEIN, of Corona, in the county of Queens and State of New York, have invented a new and useful Design, Shape, or Configuration for Single-Band Gold Bracelets; and I do hereby declare that the following is a full, clear, and accurate description of my invention, when taken in connection with the accompanying drawings, in

10 which—

Figure 1 represents a side view of the bracelet made in accordance with my invention. Fig. 2 represents a modification thereof. Fig. 3 represents a cross-section thereof, enlarged, 15 on the line *x x*, Fig. 1; and Fig. 4 represents a side view of another modification thereof.

My invention consists in a single-band gold bracelet formed of two parts hinged together at one of their ends and united by a catch or 20 the other, upon which bands are formed or attached flanges rising above the surface of the band, and between which flanges, upon the surface of the band, ornamentation in relief is formed or attached permanently, which 25 ornamentation does not rise above the upper surface of the flanges. The raised flanges, in combination with the ornamentation in relief between them, which does not rise above them, gives a very rich effect, while at the same time 30 the delicate ornamentation in relief is protected against injury by the shape or configuration of the bracelet, which enables these flanges to protect the delicate ornamentation in relief from injury.

35 My invention also further consists in burnishing the upper surfaces of the flanges, while the outer or exposed surface of the band, between the flanges, is left unburnished, is colored, or is variegated to produce a rich and 40 artistic contrast between the surfaces of the flanges and the surface of the band.

In the drawings, at Fig. 1, A A represent the two flanges projecting outward from the band. B represents the surface of the single 45 band of which the bracelet is formed, and C represents the ornamentation upon the band and between the flanges, which, by reference to the cross-section, Fig. 3, will be seen does

not project upward from the band above the flanges.

This ornamentation in relief may be of any artistic design, and may cover more or less of the surface of the band, as the designer may see fit, no particular form of ornamentation being essential to the production of the effect aimed at by me.

In Fig. 1 it will be observed that the flanges are upon and project from the extreme edges of the band.

In Fig. 2 a modification of my invention is shown, in which the flanges A A project from the band B, but are not attached to its extreme edges, a small portion of the band showing outside of each of the flanges, as at *b b*. This design has substantially the same effect to the eye as the design shown in Fig. 1, and the shape or configuration is useful in precisely the same manner as the shape or configuration shown in Fig. 1, the ornamentation C being shown as fastened upon the band and not projecting above the upper surfaces of the flanges.

Fig. 4 is another modification of my invention, in which the flanges must be near, but may not be directly upon, the extreme edges of the band B, and in which modification no ornamentation is used upon the band, the effect in this modification being produced solely by the contrast between the burnished projecting surfaces of the flanges and the unburnished or colored surface of the band. This artistic effect, produced by the differences in the surfaces of the flanges A A and band B, may be utilized in all the bracelets shown by me in the drawings attached to this specification, in any one of which the artistic effect will be increased by burnishing the projecting surfaces of the flanges A A, while the surface of the band is left unburnished or else colored. The outer edges of the flanges may be round, instead of flat, as shown.

What I desire to claim as my invention is as follows:

1. The shape or configuration of a single-band bracelet, consisting of two projecting flanges, each extending at or near one of the

(over)

edges of the band, combined with permanent ornamentation in relief upon the band between and not rising above the upper surfaces of the flanges, substantially as herein shown and described.

5. A design for a single-band bracelet, consisting of two raised flanges at or near the edges of the band, combined with ornamentation in relief upon the band between and not rising above the upper surfaces of the flanges, the upper surfaces of the flanges being of burnished gold, while the band is of colored, variegated, or unburnished gold.

3. A design for a single-band bracelet, consisting of two raised flanges at or near the edges of the band, the upper surfaces of the flanges being of burnished gold, while the surface of the band between the flanges is of colored, variegated, or unburnished gold.

In testimony whereof I have hereunto set my hand and seal this 7th day of November, 1879.

CHARLES HEIN. [L. S.]

In presence of—

PHILLIPS ABBOTT,
LEWIS J. MULFORD.
